(74) *Attorney, Agent, or Firm* — O'Connell Law Firm;
Thomas P. O'Connell(57) **CLAIM**

I claim the new and ornamental design for a building panel, as shown and described.

DESCRIPTIONFIG. 1 is an enlarged fragmented perspective view of a building panel showing my new design;
FIG. 2 is a view in front elevation of a building panel according to my invention;

FIG. 3 is a view in rear elevation of the building panel of FIG. 2;

FIG. 4 is an enlarged view in front elevation of a portion of the building panel of FIG. 2;

FIG. 5 is an enlarged view in rear elevation of a portion of the building panel of FIG. 2;

FIG. 6 is an enlarged top plan view of a portion of the building panel of FIG. 2; and,

FIG. 7 is an enlarged view in side elevation of a portion of the building panel of FIG. 2.

The broken lines in FIG. 1 are for illustrative purposes only and form no part of the claimed design.

1 Claim, 6 Drawing Sheets(56)
